Emmett E. Woodward, San Mateo, and James P. Callahan, San Francisco, Calif.; said Woodward assignor to said Callahan

Application November 11, 1935, Serial No. 59,476

Term of patent 7 years

To all whom it may concern:

Be it known that we, Emmett E. Woodward and James P. Callahan, citizens of the United States, residing at San Mateo, county of San Mateo, State of California, and the city and county of San Francisco, and State of California, respectively, have jointly invented a new, original, and ornamental Design for a Motor Vehicle Ventilator, of which the following is a specification, reference being had to the accompanying drawing, forming a part thereof.

Fig. 1 is a perspective view of our motor vehicle ventilator.

Fig. 2 is a rear view of the motor vehicle ventilator shown in Fig. 1.

Fig. 3 is a plan view of the motor vehicle ventilator of Fig. 1.

We claim:

The ornamental design for a motor vehicle ventilator, substantially as shown.

EMMETT E. WOODWARD.
JAMES P. CALLAHAN.
